AWNING

William E. Metzger, Rutland, Vt.

Application November 3, 1937, Serial No. 172,613

2 Claims. (Cl. 156—44)

The present invention relates to new and useful improvements in awnings of the roller type wherein the roller is mounted in a housing, and has for its primary object to provide, in a manner as hereinafter set forth, a novel construction and arrangement of gravity actuated door or the like for automatically closing the opening in the housing which accommodates the awning.

Another very important object of the invention is to provide novel means for mounting the roller and the door or closure in position in a manner to facilitate the removal thereof when necessary.

Other objects of the invention are to provide an awning of the aforementioned character which will be comparatively simple in construction, strong, durable, highly efficient and reliable in use, compact, light in weight, attractive in appearance and which may be manufactured and installed at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a view in front elevation of the invention, an end portion of the closure being broken away and the housing being shown in vertical section.

Figure 2 is a horizontal sectional view, taken substantially on the line 2—2 of Fig. 1.

Figure 3 is a perspective view of the closure.

Figure 4 is a view in vertical section through the invention, taken at right angles to Fig. 1.

Figure 5 is a cross sectional view through the invention, showing the gravity actuated closure in closed or operative position, the back of the housing being slightly modified.

Figure 6 is a vertical sectional view through the invention, showing the closure in raised or inoperative position.

Fig. 7 is a detail view of the clip which prevents longitudinal movement of the roller.

Referring now to the drawings in detail, it will be seen that the reference numeral 1 designates a housing of suitable material, preferably metal, which may be secured in position in any desired manner on the upper portion of a window frame 2. As shown to advantage in Figs. 4 and 6 of the drawings, the housing 1 is open at its bottom.

The end walls 3 of the elongated housing 1 have openings therein in which the trunnions 4 and 5 in the ends of a removable roller 6 are journaled. The reference numeral 7 designates a sheet of

suitable flexible material having one end secured to the roller 6 for winding thereon. The other end of the sheet 7 is connected to a U frame 8 which is pivotally and slidably mounted on side rods 9 on the window frame 2, as at 10. Also fixed on one end portion of the roller 6 is a drum 11 on which an operating cord 12 is wound.

The reference numeral 13 designates an arcuate, metallic shutter for the open bottom of the housing 1. On its ends, the shutter 13 is provided with wings or the like 14 which are journaled on the trunnions 4 and 5 of the roller 6. The wings 14 have formed therein arcuate slots 15 which accommodate the trunnions 4 and 5 and through the medium of which the closure 13 is loosely and pivotally mounted in position. On its longitudinal edges the shutter 13 is provided with beads or the like 16.

Attention is here invited to the fact that the trunnion 5 is of greater length than the trunnion 4. As illustrated to advantage in Figs. 1 and 2 of the drawings, a removable spacing clip 17 is mounted on the trunnion 5 between one end of the roller 6 and the adjacent closure wing 14. The purpose of this will be presently set forth.

It is thought that the operation of the device will be readily apparent from a consideration of the foregoing. When the cord 12 is pulled in a manner to unwind same from the drum 11, the roller 6 is actuated thereby in a direction to wind the sheet 7 thereon. This causes the frame 8 to swing upwardly to a substantially vertical position and continued winding of the sheet 7 on the roller 6 raises the upper portion of said frame into the housing 1. As the sheet 7 thus swings inwardly toward the building with the frame 8 the closure 13, which rests on said sheet 7, follows same by gravity so that when the awning has been raised the bottom of the housing 1 will have been substantially closed, as shown in Fig. 5 of the drawings. When the awning is again lowered by releasing the cord 12 the closure 13 is swung upwardly to raised position by the sheet 7, as seen in Fig. 4 of the drawings.

In the construction of housing 1 shown in Figs. 4 and 6 of the drawings, the rear wall 18 is comparatively short. When this construction is used, a horizontal rib 19 is mounted on the window frame 2, said rib projecting into the housing 1 for coaction with the lower longitudinal side or edge of the closure 13 when said closure is in lowered position. In other words, the closure 13 rests on the rib 19 when in lowered position with the awning material 7 therebetween. This substantially seals the housing 1 at this point. In

the arrangement shown in Fig. 5 of the drawings, the rear wall 18 of the housing 1 extends downwardly and terminates in a bead or rib 20 which functions in a manner similar to the rib 19. 5 The front wall 21 of the housing 1 is provided with an internal bead 22 on its lower edge which, as shown to advantage in Fig. 6 of the drawings, acts as a support for holding the closure 13 in raised position when desired. The loose pivotal 10 mounting of the closure 13 on the trunnions 4 and 5 permits said closure to be swung upwardly and then pulled outwardly or forwardly in a manner to be engaged on the bead 22.

When assembling the device, the closure 13 is 15 positioned in the housing 1 with the slots 15 aligned with the trunnion openings in the end walls 3 of said housing. The comparatively long trunnion 5 is inserted, after which the trunnion 4 is inserted by shifting the roller 6 from right 20 to left as viewed in Fig. 2 of the drawings. This leaves a space between that end of the roller 6 on which the comparatively long trunnion 5 is mounted and the adjacent wing 14 of the closure 13. The clip 17 is then mounted on the 25 trunnion 5 in this space for preventing longitudinal movement of the roller in a manner to disengage or withdraw the trunnion 4 from the opening in which it is journaled in one end of

the housing 1. To further prevent this, a removable pin 23 may be provided in the trunnion 4. It may be well to here state that the arcuate closure 13 also prevents the cord 12 from jumping 5 the drum 11.

It is believed that the many advantages of an awning constructed in accordance with the present invention will be readily understood and although preferred embodiments are as illustrated and described, it is to be understood that further 10 changes in the details of construction may be resorted to which will fall within the scope of the invention as claimed.

What is claimed is:—

1. An awning device comprising a housing having an opening therein, a roller including trunnions journaled in the housing, and a closure for the opening mounted for swinging movement on the trunnions. 15
2. An awning device comprising a housing having an opening therein, a roller including trunnions journaled in the housing, a closure for the opening pivotally and slidably mounted on the trunnions, and means in the housing engageable beneath the closure for supporting same in 20 open position. 25
